US00D45411S

(12) **United States Design Patent** (10) Patent No.: **US D454,111 S**
(45) Date of Patent: **** Mar. 5, 2002**

(54) **HIGH DENSITY, HOT PLUGGABLE POWER SUPPLY**

D445,761 S * 7/2001 Weng D13/110

* cited by examiner

(75) Inventor: **Edward Rodriguez**, Winchester, MA (US)

Primary Examiner—Joel Sincavage

(74) Attorney, Agent, or Firm—Edwin H. Paul, Esq.

(73) Assignee: **Unipower Northeast Technical Center**, Westford, MA (US)

(57) **CLAIM**

The ornamental design for a high density, hot pluggable power supply, substantially as shown.

(**) Term: **14 Years**

DESCRIPTION

EMBODIMENT 1:

FIG. 1 is a front view of a high density, hot pluggable power supply incorporating the design;
FIG. 2 is a top plan view thereof;
FIG. 3 is a left-side view thereof;
FIG. 4 is a right-side view thereof;
FIG. 5 is a bottom view thereof; and
FIG. 6 is a back view thereof;

EMBODIMENT 2:

FIG. 7 is a front view of a high density, hot pluggable power supply incorporating the design;
FIG. 8 is a top plan view thereof;
FIG. 9 is a left-side view thereof;
FIG. 10 is a right-side view thereof;
FIG. 11 is a bottom view thereof; and,
FIG. 12 is a back view thereof.
